UNITED STATES PATENT OFFICE

169,688

FOLDABLE CLOTHESRACK

Gustav H. Meister, Bath, Maine

Application May 16, 1952, Serial No. 19,745

Term of patent 3½ years

(Cl. D33—8)

To all whom it may concern:

Be it known that I, Gustav H. Meister, a citizen of the United States, residing at Bath, in the county of Sagadahoc and State of Maine, have invented a new, original, and ornamental Design for a Foldable Clothes Rack, of which the following is a specification, reference being had to the accompanying drawings, forming a part thereof.

Fig. 1 is a top plan view of a foldable clothes rack, the supporting rods being in extended position, showing my new design;

Fig. 2 is a side elevational view thereof;

Fig. 3 is an enlarged front elevational view thereof, the supporting rods being shown in folded position;

Fig. 4 is an enlarged top plan view thereof;

Fig. 5 is an enlarged longitudinal sectional view thereof taken on line 5—5 of Fig. 3.

I claim:

The ornamental design for a foldable clothes rack, as shown.

GUSTAV H. MEISTER.
